MULTICIRCUIT QUARTER WAVE PULSE JET
ENGINE

Albert G. Bodine, Jr., Van Nuys, Calif.

Application January 12, 1948, Serial No. 1,733

15 Claims. (Cl. 60—35.6)

1

This invention relates generally to resonant quarter-wave pulse jet engines, and more particularly to resonant quarter-wave pulse jet engines of multiple circuit and polyphase character.

The present invention is a continuation-in-part of my prior parent application Serial No. 439,926, filed April 21, 1942, entitled Resonant Wave Pulse Engine and Process (now abandoned), and also of my copending application Serial No. 753,898, filed June 11, 1947, entitled Pulse Jet Standing Wave Engine with Movable Wave Reflecting Means. See also my copending application Serial No. 783,662, filed Nov. 3, 1947 as a continuation-in-part of my said parent application Serial No. 439,926, entitled Resonant Wave Pulse Engine and Process, and issued August 30, 1949 as Patent No. 2,480,626.

Resonant quarter-wave pulse jet engines utilized for jet propulsion have been disclosed in my prior applications, and a detailed description will not be required herein though reference may be made for that purpose to my aforesaid prior and copending applications. It will suffice here to say that such an engine typically involves a substantially quarter-wave pipe, closed at one end and open at the other, with provision for burning increments of fuel and air in its closed end at a resonant frequency of the pipe so as to create intermittent positive pressure pulses establishing a standing wave therein. Auxiliary air may be introduced to the closed end of the pipe, and this air, together with products of the combustion, travels down the pipe to be discharged from the open end thereof. Air is also drawn laterally inward toward the open end of the pipe and thence up the pipe for a distance, to be then discharged straight rearwardly from the open end of the pipe.

Such engines in large power size have the disadvantage of excessive production of vibration and noise, and limitation on power output; and the general purpose of the present invention is the provision of a quarter-wave pulse jet engine which overcomes these disadvantages.

The engine provided by the present invention may be regarded broadly as a "multiple circuit" wave pulse jet engine, by which term I refer to a wave pulse jet engine having two or more resonated pipes, with either uniform or non-uniform phase relations between them. In distinction thereto, and by analogy with electrical engineering practice, I employ the expression "polyphase" engines to denote the narrower class of multiple circuit engines with substantially uni-

2

form phase relations. Thus an engine having two pipes operating with waves of 180° phase difference is a two-phase polyphase engine, one having three pipes with waves of 120° phase difference is a three-phase polyphase engine, etc. In general, the benefits of the present invention are gained in a multiple circuit engine having non-uniform phase relations, but these advantages are realized to the maximum extent when 10 the phase relations are made uniform throughout.

A primary object of the invention is the provision of a multiple circuit quarter-wave pulse jet engine, and a further object is the provision 15 of such an engine characterized by uniform phase relations, i. e., "polyphase" operation.

A multiple circuit quarter-wave pulse jet engine in accordance with the invention may be one whose pipes or resonant fluid columns are 20 separate from one another, i. e., have no internal intercommunication, or one whose fluid columns do communicate with one another internally of the apparatus. In the latter instance, the communicating fluid column may have but a 25 single fluid discharge opening. In both types, polyphase operation may be established automatically, by virtue of acoustic self-coupling. The couplings may also, or alternatively, be of mechanical character.

Multiple circuit quarter-wave pulse jet engines 30 in accordance with the invention may be arranged with the resonant pipes either side by side, or in staggered or longitudinal spacing.

In my multiple circuit engines the sound waves emanating from the several pipes thereof tend to 35 cancel one another at a distance from the engine, with the result that objectionable noise is reduced. In the region of the jets of the several pipes, on the other hand, the waves interact upon 40 one another in such a way as to effect a desirable acoustic self-coupling leading to polyphase operation. In this regard, it will later become apparent that substantial gas velocity oscillations occur at the discharge opening of the several 45 pipes, these discharge openings being the locations of velocity anti-nodes of substantially equal acoustic impedance. When these discharge openings are located in correct proximity to one another, the oscillations tend to synchronize so as 50 to give polyphase operation. Thus two quarter-wave pipes having automatic valves and substantially equal resonant frequencies operating side by side with sufficient acoustic coupling will automatically fall into step, with their waves 180° 55 out of phase with one another.

Polyphase operation has the further advantage of giving an effect of higher frequencies where both noise and vibration are more greatly attenuated at a distance, where an observer might be standing. Further, by dividing the total power of an engine between several circuits, each explosion is of correspondingly reduced intensity, to obvious all-around advantage.

The advantages of multiple circuit pulse engines mentioned in the foregoing are realized even with random phase relations, with no positive or mechanical linking between circuits. However, as already mentioned, the several units of a multiple circuit engine tend automatically to link together by acoustic self-coupling and thus to operate with polyphase relationships.

As a further consideration, it is known that there is a maximum effective diameter (approximately

$$\frac{\lambda}{10\pi}$$

where λ = wave length) for the pipe of a jet propulsion apparatus of the present type. Above that value, wave reflection becomes bad at the open end of the pipe. Increase in the diameter of the pipe for added power, without increase in the wave length, and therefore in the pipe length, is accordingly limited. The use of a multiple circuit engine permits increase in power without increase in pipe length.

The invention will be further described in connection with the accompanying drawings showing present illustrative embodiments thereof, and wherein:

Figure 1 is a somewhat diagrammatic partly elevational and partly sectional view showing one embodiment of the invention;

Figure 2 is a similar view showing another illustrative embodiment of the invention;

Figure 3 is a medial longitudinal sectional view of a still further illustrative embodiment of the invention;

Figure 4 is a perspective view of the internal parts of the embodiment of Figure 3;

Figure 5 is a medial longitudinal sectional view of still another illustrative modified form of the invention;

Figure 6 is a somewhat diagrammatic view, partly in section, showing a modification of the embodiment of Figure 2;

Figure 7 is a side elevation, partly in longitudinal section, showing another modified embodiment of the invention; and

Figure 8 is a section taken on broken line 8—8 of Figure 7.

Figure 1 of the drawings shows a multiple circuit polyphase wave pulse engine of a type in which synchronization is accomplished by mechanical coupling. Three sonic pipe units 10 are employed, positioned side by side, and in a general way parallel to one another, though they may be arranged with a small angle between their respective longitudinal axes for an optional purpose to be mentioned hereinafter. These sonic pipe units 10 are identical with one another, and are provided with identical combustion means, so that a description of one will serve for all. Each pipe unit 10 thus has a somewhat flared open end 12, through which air is alternately drawn in from virtually all directions and then discharged straight rearwardly to produce a jet propulsion thrust. The opposite end of the pipe 10 has a flange connection 13 with a closure head 14 defining a somewhat restricted combustion space 15. 75

Though not an essential, the illustrative embodiment includes, mounted between the rearward or flanged end of pipe 10 and the head 14, a piston-type flexible diaphragm 16 consisting of a relatively rigid piston portion 16a joined by an elastic compliance 16b to a marginal rim portion which is clamped between the adjacent flanges on the pipe 10 and the head 14.

As will later appear, this diaphragm oscillates or vibrates in step with the frequency of combustion within chamber 15 (being driven by that combustion) and operates to transmit the pressure pulses developed in the combustion chamber to the fluid column in pipe 10.

Cooperating with a suitable valve seat formed within head 14 is an intake valve 20 supplied with a combustible mixture through a pipe 21 to which the mixture is fed from a supercharger 22, the mixture being formed by carburetor 23. Also co-

operating with a suitable valve seat formed within head 14 is an exhaust valve 25 controlling the flow of exhaust gases through a passage 26. The intake and exhaust valves are operated in sequence by cams 27 and 28, respectively, on a cam shaft 29 which drives the supercharger 22 and magneto 30, and which is here shown as driven by a drive means 31, which may consist of any suitable gear means interconnecting with a single drive shaft 32 driven by a main drive unit 33. The latter may be any speed-governed drive, such as an electric motor, internal combustion engine, turbine, etc.

As an alternative or supplemental fuel supply means, there may be provided a fuel injector pump 34 driven from cam 34a on cam shaft 29 and acting to meter liquid fuel directly into the combustion chamber through a suitable spray type injection nozzle 34b. Fuel can be mixed with the air in the carburetor 23 to form a lean mixture delivered to the combustion chamber through intake valve 20, and additional fuel in liquid state can be supplied, preferably during periods of high pressure in the combustion chamber, by use of the injector pump. Alternatively, the carburetion system or the injection system may be utilized individually, and if it be desired to inject all the fuel into the combustion chamber, the necessary air for combustion will be supplied through the intake valve from the supercharger. In the latter case, the combustion is timed and synchronized by air introduction under control of the cam driven intake valve. The magneto and cams 27, 28 and 34a are of course arranged to provide the desired operative sequence of events including introduction of fuel, ignition (as by use of spark plug 35 connected to magneto 30) and exhaust of the combustion products.

The events of the operating cycle include, in sequence, (1) delivery of the fuel charge to the chamber 15 upon opening of the intake valve and movement of the vibratory diaphragm 16 toward the right, (2) compression of the admitted fuel charge on return movement of the diaphragm (toward the left), (3) ignition of the fuel charge and consequent creation of a positive pressure pulse which drives the diaphragm back toward the right, causing the pressure pulse to be transmitted to the fluid column, and (4) opening of the exhaust valve and return of the diaphragm to scavenge the combustion chamber.

The speed of the cam shaft 29 of each unit is such that the explosions generated in combustion chamber 15 occur at such frequency as will establish a condition of standing wave resonance in the fluid column within the pipe 10,

the pipe behaving substantially as a quarter-wave organ pipe, with a pressure anti-node region P adjacent the closure formed by diaphragm 16, and with a velocity anti-node V at the open end 12. It will, of course, be understood that for a pipe of given length, there will be a corresponding explosion frequency necessary to establish the desired resonant operation, and the cam shaft 29 is driven at a speed to achieve such a condition. One method of accomplishing this purpose is to note the peak reading of a pressure gauge 36 communicating with the pressure anti-node region P of the apparatus. This gauge will show a maximum reading at resonance. The reading on the gauge 36 will indicate the magnitude of the propulsive thrust, since the thrust results, at least in part, from the action of each wave pulse against the diaphragm 16 in accordance with radiation pressure principles set forth in my aforesaid application Serial No. 439,926.

It may be noted that diaphragm 16 should be stiff enough to reflect pressure waves returning to it from the open mouth 12 of the pipe in the general manner of the closed end of a quarter-wave organ pipe. In view of the travel of the diaphragm, a region P of zero to-and-fro oscillation cannot be achieved, but a substantial pressure anti-node P is established.

The operating cycle of the apparatus is as follows: The explosion within chamber 15 creates a pressure disturbance producing a positive pressure pulse which moves diaphragm 16 to the right, thereby transmitting the positive pressure pulse to the end of the fluid column within the pipe 10 and thence toward the right along the fluid column, the wave traveling with the speed of sound to the open end 12 of the pipe, which expands it into the open atmosphere. Normally the diaphragm will be substantially at its extreme position toward the left at the instant of explosion. At a time substantially 90° following the explosion, the diaphragm passes through the mid-position of its forward or power stroke travel toward the right, and at such time transmits peak positive pressure to the end of the fluid column. The diaphragm will thereafter complete its stroke to the right and then move through a return stroke (leftward) by virtue of the energy stored in its stressed compliance.

The positive pressure pulse launched down the pipe by the described forward stroke of the diaphragm is reflected from the open end of the pipe as a negative pressure pulse (wave of rarefaction), the peak of which arrives at the diaphragm one-half cycle after the positive pressure pulse peak at the diaphragm and just as the diaphragm is at the mid-point of its return stroke (leftward). The diaphragm continues toward the left, and this movement together with the negative pressure pulse already mentioned creates a substantial pressure depression in the region immediately to the right of the diaphragm. The said return stroke of the diaphragm (toward the left) operates to scavenge the combustion chamber, the exhaust valve 25 being open at this time. The described negative pressure pulse is reflected by the diaphragm as a negative pressure pulse moving toward the right, which is reflected from the open end to return a half-cycle later as a positive pressure pulse that arrives at the diaphragm with peak positive pressure as the diaphragm passes with maximum velocity through the mid-position on its next forward stroke (toward the right). A positive pressure peak is thus built up to the right of the diaphragm, while

a suction is created within chamber 15 by which fuel is taken in through the then open intake valve 20. A positive pressure pulse is then reflected from the diaphragm, and returns a half-cycle later (after reflection at the open end) as a negative pressure pulse reaching the diaphragm with peak pressure as the latter passes through the mid-position of its compression stroke (leftward). The negative pressure pulse is in turn reflected by the diaphragm and a half-cycle later will return from the open end as a positive pressure pulse arriving with peak positive pressure just as the diaphragm passes through its mid-position on the succeeding "power" stroke. A positive pressure peak will thus again be created to the right of the diaphragm as the diaphragm crosses the mid-point of its forward power stroke, and the succeeding cycle proceeds as before. The maximum pressure in the chamber 15 occurs instantaneously after the explosion, when the diaphragm is in its extreme leftward position. The maximum positive pressure in the region immediately to the right of the diaphragm occurs 90° of the cycle later, with the diaphragm at the half-way point of its return stroke, moving with maximum velocity. The pressure wave at the head end of the fluid column in pipe 10 thus lags by 90° the pressure events in the combustion chamber, the intervening diaphragm functioning as a coupling introducing substantially a 90° phase lag.

It will be seen that the pipe 10 behaves as a quarter-wave organ pipe, cyclically excited by intermittent combustion generated pressure pulses at a sub-multiple (here one-half) of its resonant frequency. In accordance with quarter-wave pipe theory, a standing wave is established in the pipe, with a pressure anti-node P adjacent the diaphragm 16, and a velocity anti-node V at the open end or tail 12. At the pressure anti-node P, as well as within the combustion zone 15, alternate positive and negative pressure peaks are experienced, and these create a radiation pressure thrust on the diaphragm in accordance with principles explained in my application Serial No. 439,926. At the pressure anti-node zone P, to-and-fro oscillation of the fluid is, of course, minimized. At the velocity anti-node region V, however, the air moves to-and-fro into and out of the open end of the pipe with substantial amplitude. Outside air is alternately drawn into the end of the pipe from virtually all directions, and expelled in a rearward axial direction, thereby creating a thrust by jet discharge.

The foregoing description of operation is confined to a single unit. To secure polyphase operation, the cams on the three cam shafts 29 are arranged 120° out of phase, which of course equally spaces the explosions (and therefore the jet discharge pulsations) of the three units at 120° phase relationship. The beneficial results of this polyphase operation include increased frequency, increased attenuation of noise and vibration, and reduction of noise at a distance from the engine by mutual cancellation of the three sound waves delivered out-of-phase by the three units. In addition, improved power output can be achieved in such a polyphase engine as compared with a single pipe unit having a pipe of a cross-section equal to the total cross-section of the three employed in the present embodiment of the invention.

The use of the three pipes, with small angles between their longitudinal axes, as in Figure 1, also permits directional control of a craft to which the engine may be attached. Thus it

should be evident that cutting out either of the outside pipes will vary the resultant direction of thrust in the apparatus, and that various combinations are possible to achieve a substantial degree of directional control.

Reference is next to the embodiment of Figure 2, showing a multiple circuit engine employing acoustic coupling, in this specific instance, accomplished internally of the apparatus. In this embodiment there are provided two quarter-wave pipes 50 and 51, having closed forward ends 52 and 53, respectively, and the far or rearward end portions of which are curved towards one another and joined. The joined rearward ends of the pipes are provided with a single, common jet discharge opening or outlet 55. It will thus be seen that the two pipes 50 and 51 contain gas columns which are in internal communication with one another.

The closed or forward ends of the two pipes 50 and 51 are connected to wave-controlled combustion means 56 and 57, respectively, which may be of various natures, and two examples of which are shown connected to the two pipes 50 and 51. Each such wave controlled combustion means comprises generally a means for burning a combustible charge at the resonant frequency of the corresponding pipe, so as to establish a quarter-wave standing wave therein. Each such standing wave will be characterized by the appearance of a pressure anti-node at the closed end of the pipe, designated at P and P' for the pipes 50 and 51, respectively, and a velocity anti-node V at the rearward portions of the pipes, immediately adjacent the common discharge outlet 55. With no mechanical interconnection between the two combustion means 56 and 57, the two standing waves of the two pipes 50 and 51 are synchronized owing to a "push-pull" interaction of the gas columns at the velocity anti-node region V so as to establish polyphase operation with 180° phase difference between the two sides of the system.

The wave controlled combustion means 56 as here shown includes a fuel injection nozzle 60 adapted to introduce fuel to combustion zone 61 and connected by fuel line 63 to injection pump 64 which delivers a charge of fuel each time its plunger 65 is raised. Pump 64 is actuated by an arm 66 pivoted at 67 and operatively connected to rod 68 attached to diaphragm 69. This diaphragm works in a housing 70 forming chambers 71 and 72 therein, which are in restricted communication through a small orifice 73. Chamber 72 is substantially sealed from the atmosphere at the junction of the rod 68 and the housing. Chamber 71 is in relatively open communication with combustion zone 61 through orifice 74 which is larger in size than orifice 73.

An air intake valve 75 opens into combustion zone 61 and provides a stem terminating in a pressure plate 76 disposed to be engaged by arm 66 to open the valve 75 against a valve spring 77. Valve 75 controls the flow of air from air intake passage 78 formed by intake pipe 79, the far end of which is preferably bent and flared to provide a mouth 81 for the air stream created by motion of the apparatus.

In this embodiment, compression in combustion zone 61 is depended upon to cause ignition, such compression resulting from pressure peaks owing to the previously mentioned standing wave. However, to aid the compression ignition, the combustion chamber may provide a collar-like member 85 providing a slightly restricted passage 86 opening on the combustion zone 61. The heat of

this member will be sufficient, at the value of the pressure pulses in the sonic column, to ignite the fuel in a manner similar to that employed in so-called "hot tube" or "hot head" combustion engines. To aid in the starting of the device, the member 85 may be heated by such a means as an annular electric heating element 87 which can be used within or adjacent the member 85 to supply initial heat for starting.

The wave control combustion means 57 may be of exactly the same character as the means 56, though it is here shown in somewhat different form. Here, ignition depends upon spark plug 90 connected to intake coil 91, the low voltage circuit of which includes the source of current 92 and a make-and-break switch 93 similar to that employed in conventional automotive practice. Switch 93 is actuated by plunger 94 connected to diaphragm 95 urged downward by spring 96, the low side of the diaphragm communicating through passage 97 with the fluid column 60 at zone P'. Upon the appearance of a positive pressure pulse at P, diaphragm 95 moves upward to open switch 93 and break the low voltage circuit, thus inducing in the high tension winding a voltage sufficient to cause the plug 90 to spark. The sparking of this plug will be synchronized with and by the appearance of pressure pulses in the zone P'.

A combustible mixture is introduced into zone P' through intake valve 100, which is of an inwardly opening spring-loaded type, so that it opens whenever the pressure in a fuel induction passage 101 exceeds the pressure at P' by a pre-determined amount, thus insuring delivery of a combustible mixture during period of rarefaction at P', the charge being later ignited upon the appearance of the following pressure pulse at this zone. A supercharger 102 supplies the air-fuel mixture to passage 101, the mixture being supplied to the supercharger via carburetor 103 and pre-heater 104 surrounding pipe 51.

Operation is as follows: an explosion in zone P of pipe 50, caused by burning fuel in combustion zone 61, establishes a positive pressure pulse which travels at the speed of sound through the fluid column in the pipe 50 from the closed end thereof in the direction of the discharge outlet 55. In a similar manner, an explosion in zone P' of pipe 51, caused by burning fuel in the combustion zone thereof, establishes a similar positive pressure pulse traveling at the speed of sound through the fluid column in the pipe 51 in the direction of the common discharge outlet 55.

It should be evident that the two positive pressure pulses thus generated in the two pipes 50 and 51 will, if created substantially simultaneously, buck one another at the velocity anti-node zone V. The tendency, however, is for the two interacting waves quickly to assume a relationship of 180° phase difference, where the two positive pressure waves in the two pipes 50 and 51 no longer buck, but operate in a "push-pull" fashion, each aiding the other. Thus the powerful velocity oscillations of the two gas columns at the velocity anti-node zone V acoustically couple the two sides of the system, synchronizing the two standing waves to operate with 180° phase difference. The explosions at the combustion zones of the two pipes then occur alternately, in 180° phase opposition.

Each explosion at zone P accordingly sends a positive pressure wave traveling toward the right in pipe 50. At the instant of this explosion in pipe 50, a rarefaction prevails at zone P' in pipe

61, causing intake valve 100 to open, and fuel to be discharged to the zone P'. At the subsequent peak of positive pressure in zone P', plug 90 sparks as already described to ignite the fuel charge at P', so that a positive pressure wave is launched toward the right in pipe 51. At this same time, a pressure depression or rarefaction exists at combustion zone 61, causing air intake and fuel injection to said zone 61, as explained hereinbefore. The subsequent peak of positive pressure in zone 61 compresses this charge to the point of self-ignition, whereupon the cycle is repeated. The result is the creation of a standing wave characterized by the pressure anti-node P at the head end of pipe 50, a pressure anti-node P' at the head end of pipe 51, and a velocity anti-node V at their point of intercommunication. Combustion gases progress toward the right in both pipes 50 and 51 and are discharged via outlet 55 to form a propulsive jet. A propulsive thrust is also obtained by radiation pressure principles as discussed fully in my parent application Serial No. 439,926. See also my Patent No. 2,480,626.

The embodiment of Figure 2 thus consists of a two phase, polyphase engine, characterized by lack of mechanical intercoupling between the two pipes, and by the provision of acoustic self-coupling internally of the apparatus. It should be evident that the embodiment of Figure 2 illustrates a type of acoustic coupling for polyphase operation which is operative whether or not the coupling is made effective internally of the pipes. Figure 6 shows, somewhat diagrammatically, a modification of Figure 2 in which acoustic coupling is achieved externally of the pipes. Two pipes 50a and 51a may have at their closed forward ends wave controlled combustion means 56a and 57a, like the corresponding means 56 and 57 of Figure 2, and may have their rearward end portions placed side by side, and open at their extremities. Standing waves are established in both pipes, with pressure anti-nodes at P and P' and velocity anti-nodes at V and V'. The velocity anti-node regions are characterized by powerful velocity oscillations in the surrounding fluid, both within the end portions of the pipes, and in the general area immediately around and to the rear of the rear open ends of the pipes. Acoustic self-coupling between the two pipes occurs by the interaction of these velocity oscillations, exactly in the manner described in connection with Figure 2, though of course with somewhat lessened effect. The intercoupling so achieved, however, is still enough to bring about polyphase operation (equal phase angles) with no other interconnection between the two sides of the system.

Reference is next directed to the embodiment disclosed in Figures 3 and 4, showing a polyphase engine enclosed in a streamlined shell, and employing certain further improvements. Numeral 130 designates generally a cluster of sonic pipes 131, symmetrically disposed about a central longitudinal axis, and in this instance five in number. Each of these pipes has a forward end closure 132, and an open rearward end 133. Connected to the head ends 132 are fuel and air intake pipes 134, which converge in a forward direction and merge with the five segment-like cells or passages 135 of a fuel and air intake cylinder 136. The latter consists of a cylindrical shell, divided by longitudinal, radial walls 137, so as to form passages open at the forward and rearward ends of the cylinder. The passages 135 at the rearward end have already been described 75

as connected to the intake pipes 134. The forward ends are open for intake of fuel and air.

Numeral 140 designates an elongated streamlined shell, preferably of circular section, having its greatest section at approximately its longitudinal midpoint and being slightly convergent toward its open or tail end 141, and somewhat more convergent toward the open forward end or nose 142. The pipes 131 are disposed within the rearward portion of this shell, and the cylinder 136 is located somewhat forwardly, and on the longitudinal central axis of the shell. Suitable supporting and bracing means may be provided for the support of the cylinder 136 and pipes 131 within the shell, as indicated at 144. Disposed in the forward end portion of the shell, forwardly of cylinder 136, is a streamlined body 150 supporting a fuel distributor pipe 151, together with a drive motor 152 for the latter. This body 150 is annularly spaced inside the forwardly converging walls of the shell, so as to provide an ample air flow passage therearound. Thus air taken in at the open nose 142 flows rearwardly around the body 150, a portion of it entering the passages 135 for direct intake into the pipes 131, and another portion flowing rearwardly past the outside of the cylinder 136, and around the outside of the pipes 131, to serve a later described desirable function at the rearward ends of the pipes 130.

The fuel distribution pipe 151 consists of an axial pipe portion 160 mounted in bearings 154 and 155 in body 150, and having mounted thereon the rotor 163 of electric motor 152, the stator 164 of the latter being fixed within the body 150 as indicated. A fuel passage 165, supplied by means of fuel line 166, supplies fuel to a chamber 168 surrounding a short length of pipe portion 169, this chamber 168 being packed off around member 160 by means of suitable packing glands 161 and 162 as indicated. Apertures 170 in pipe portion 160 permit fuel to enter the interior thereof. Rearwardly of the body 150, the pipe 151 has a portion 171 extending laterally from the axial portion 160, and extending rearwardly from the extremity of portion 171 is a fuel injector nozzle 172, the latter being located immediately forwardly of the cylinder 136, so as to inject fuel into the several passages 135 depending upon its position at any given instant. It will be evident that the motor 152 will rotate the pipe 151, and so cause the nozzle 172 to project fuel charges into the several passages 135 in turn.

Each pipe 134 together with the corresponding passage 135 is preferably of a length equal to one-quarter the wave length corresponding to the fundamental resonant frequency of the pipe 131. With such dimensions, the juncture of the intake pipe 134 with the pipe 131 may be valveless, as explained in my copending application filed February 15, 1947, Serial No. 728,766, for Standing Wave Jet Propulsion Apparatus With Valveless Air Intake Conduit, in which said feature is disclosed and claimed.

Considering first the operation of a single pipe 131, air intake pipe 134 with the corresponding passage 135 delivers a continuous flow of air to the head end region of pipe 131, and an intermittent fuel charge thereto, depending upon the timing of fuel distributor 151. The mixture is ignited as by means of spark plug 175, and the resulting explosion creates a positive pressure pulse or wave of condensation traveling with the speed of sound in the column of gas in pipe 131 toward the rearward open end of the latter. This

wave will be reflected from said open end of a negative wave or wave of rarefaction, which will in turn be reflected by the head 132 as the wave of condensation. The last mentioned wave of condensation, arriving at the head end region of the pipe, increases the pressure thereat, and the fuel mixture introduced via the pipe 134 subsequent to the last explosion has its density within the head end region of the pipe thereby sufficiently increased to cause a second explosion. The flame never completely extinguishes between explosions, but the reduced pressure and fuel-air mixture density prevailing between positive pressure peaks inhibit and attenuate combustion to a point that only sufficient flame is retained to insure explosive combustion on subsequent pressure peaks. Thus it will be seen that the spark plug need be employed only on starting, compression ignition being available thereafter. The pipe 131 behaves as a quarter-wave organ pipe, cyclically excited at its resonant frequency under positive control if the fuel distributor pipe 151 is operated at such a speed as to provide fuel charges to the pipe at the said resonant frequency of the pipe. It is therefore desirable to provide the proper relationship between the speed of the fuel distributor motor 152 and the fundamental frequency of the pipe 131. The relationship will be correct if motor 152 rotates at a R. P. M. equal to the fundamental wave frequency of the pipe 131.

The zone P will be understood to be the location of a pressure anti-node P, where alternate positive and negative pressure peaks are experienced. At the velocity anti-node region V gas flows to and fro into and out of the pipe with substantial amplitude. Air supplied by the air stream flowing rearwardly around the pipe 131, is drawn first into the end of the pipe 131, and then expelled in a straight rearward direction, along with a quantity of combustion gases, to develop a jet propulsive thrust.

It will be evident that the fuel distributor pipe 151 delivers fuel charges to the several intake pipes of the cluster of sonic pipes 131 in succession, thus positively establishing polyphase, which in this instance is five phase.

The apparatus of Figure 3 has the benefit of increased frequency, reduced noise production, augmented power for a given length of sonic pipe, and general all around simplicity. The polyphase operation is here established by the synchronizing fuel distributor, and acoustic coupling is not required. It should be evident, however, that a cluster of pipes placed side by side as in Figure 3 will automatically assume a moderate degree of polyphase operation by acoustic self-coupling in the regions of the discharge openings of the pipes 131 even though the synchronous fuel distributor not be employed. Such intercoupling resembles that described in connection with the embodiment of Figure 2, where the gas columns in the two sided system are in communication internally of the apparatus. Similar coupling, though of course not so strong as in the case of Figure 2, will result when the gas columns communicate externally of the pipes, as in Figure 6. Such acoustic intercoupling will occur with pipes disposed and spaced as indicated in Figure 3.

In the previously discussed embodiments of the invention, the sonic pipes are disposed in side by side relationship. They may also be disposed in staggered or longitudinal spacing, and the em-

bodiment disclosed in Figure 5 is illustrative of such an arrangement.

The apparatus of Figure 5 is shown to employ an external streamlined shell 200, preferably of circular section having its greatest thickness at approximately its mid-section, and being slightly convergent toward its open tail end 201, and also somewhat convergent toward its open forward end or nose 202. A streamlined diffuser body 205 is positioned on the longitudinal axis of shell 200 in the forward portion of the latter, providing an annular air passage 206 extending therearound in a rearward direction. Rearward of the diffuser body are a plurality of longitudinal rows of longitudinally spaced or staggered quarter-wave pulse jet units 210. In the present embodiment, for simplicity, there are two of these rows of units, diametrically opposed from one another, though it will be understood that additional rows 20 may be provided. In the present embodiment, each of the rows consists of three of the units 210, and these units 210 are, generally speaking, of the same type as the individual pipes 131 of Figure 3. See also my aforementioned prior application Serial No. 728,766, for a more complete discussion of this type of unit.

Each unit 210 has a sonic pipe 215 formed with an end closure 216 upstream of the air flow through the shell 200, and with an open end 217, the latter projecting, with clearance, into an annular passage or port 218 extending outwardly and rearwardly through the side of the shell 200. The head end of each of the pipes 210 is also fitted with a quarter-wave air and fuel intake pipe 35 219 of the type completely described in my aforesaid application Serial No. 728,766, said pipe 219 being provided with an injector nozzle 220 fed by a fuel line 221.

The several fuel pipes 221 are supplied with fuel 40 from a distributor pump 222 located inside diffuser body 205, said pump being driven by any suitable means such as an electric motor 223 and fed with fuel by way of fuel line 226 from fuel tank 227 located in the forward portion of body 205. It is to be understood that the pump 222 is designed to feed increments of liquid fuel 45 successively to the several fuel lines, whereby the several pulse jet units 210 will be supplied with fuel charges in a predetermined succession. Various firing orders may be provided. One simple 50 arrangement is to design the pump 222 to deliver charges of fuel to the three units 210 of each longitudinal row in succession, at uniform timed intervals, so that they will operate in a three phase fashion. The pump can be designed 55 to deliver charges of fuel to the diametrically opposite row in exact synchronism with the first row, so that three phase operation is obtained, with corresponding units on opposite sides of the apparatus firing simultaneously. Alternatively, 60 the pump 222 can be designed to deliver fuel charges to the units 210 of the second row in between the delivery of fuel charges to the units of the first row, thus giving six phase operation, 65 with externally experienced sound at doubled frequency.

In operation, air taken into the apparatus through the nose 202 will enter the several intake pipes 219, and will form mixtures with the fuel 70 charges supplied by the injector nozzle 220, which mixtures are delivered to the head end regions of the pipe 215, the order of delivery being of course predetermined in the design of the pump 222. Ignition may be initiated as in the 75 earlier described embodiments, and in opera-

tion, each unit will deliver combustion gases from its rearward open end in the form of a propulsive jet which discharges through the side of the shell 200 by way of the orifice provided. Operation is characterized by the establishment of a pressure anti-node P in the head end of the pipe 210, and a velocity anti-node V at the open end thereof. It should be unnecessary to again describe the operating cycle, which has already been adequately discussed in connection with previous embodiments. Attention is, however, directed to the fact that the air stream flowing rearwardly through the shell 200 supplies air to the velocity anti-node regions V of the open ended pipes 215, such air being drawn laterally in and then up the pipes for a distance, and thereafter expelled straight rearwardly of the pipes to add to the mass of the jet discharge.

The pipes 215 of the embodiment of Figure 5 are shown as provided with some convergence in the rearward direction, this being of advantage for a reason disclosed in my Patent No. 2,480,540. In the specific arrangement of Figure 5, the convergent rearward end portions of the first and second units 210 in each row are somewhat overlapped by the intake pipes 219 of the units immediately to the rear, thus giving what might be regarded as a staggered relationship. Disregarding the intake pipes 219, however, the main pipes 215 of the successive units in Figure 5 form a longitudinal row, with longitudinal spacing between pipes.

Reference is next directed to the embodiment illustrated in Figures 7 and 8. Numerals 130 and 131 show a symmetrical pair of convergent horn-like resonant pipes or cavities providing a pair of generally parallel fluid conduits, the small or neck ends of which communicate with a piston chamber 132 of a two cylinder, free piston engine designated generally by numeral 133. Engine 133 employs a pair of opposed, axially aligned engine cylinders 134 and 135.

Each of cylinders 134 and 135 joins the chamber 132, which is defined by a cylindrical sidewall 136, and angular endwalls 137, disposed at angles of approximately 60° to the axis of the cylinders, as clearly shown in Figure 7. The smaller end portions of the conduits 130 and 131 are curved somewhat toward one another and joined to the angular walls 137 of chamber 132 at substantially right angles thereto, the walls 137 being ported so that the conduits 130 and 131 communicate freely with the chamber 132. The far or open ends of conduits 130 and 131 discharge in substantially parallel directions, perpendicular to the axis of the engine cylinders 134 and 135. As already mentioned, the conduits 130 and 131 are preferably somewhat divergent, though not as divergent as might appear from Figure 7, there being preferably a moderate convergence in the plane at right angles to Figure 7, as will appear from an inspection of Figure 8. Overall, the conduits 130 and 131 may be considered to have, preferably, a small degree of divergence, though this is not essential to the invention.

The engine 133 is illustratively, though not necessarily, of a two-cycle type, and each of cylinders 134 and 135 is accordingly provided with an appropriate fuel-air intake pipe 140, air being understood to be drawn in through the flared scoop-end 141 thereof, and a fuel mixture being formed by carburetor 142. Each of cylinders 134 and 135 is provided with an exhaust pipe 144 connected in the manner conventional in two-

cycle engines. These exhaust pipes 144 may discharge to atmosphere preferably in the same direction as the discharge from conduits 130 and 131 (see dotted line indication), but as here shown they are connected to the convergent end portions of the conduits 130 and 131. In this connection, for a reason which will appear presently, the exhaust from cylinder 133 is introduced to conduit 131, and the exhaust from cylinder 135

10 is introduced to conduit 130.

Working within cylinders 134 and 135 is a unitary free piston structure 150 consisting of a piston 151 working within cylinder 134, a piston 152 working within cylinder 135, and an enlarged 15 "acoustic" piston 153 working within enlarged chamber 132, the piston 153 having angular sides 154 of the same angle as the angular end walls 137 of chamber 132, so that clearance space between the acoustic piston 153 and the ends of 20 the chamber 132 may be reduced substantially to zero. The heads of the two cylinders are provided with spark plugs 160, and these are energized under the control of the reciprocation of the free piston. As one illustrative expedient, 25 the piston member 153 may be provided with a cam rod 161 projecting oppositely therefrom and outwardly through suitable close-fitting passages in the endwalls 137 of chamber 132. Opposite ends of this cam rod are formed with cam surfaces 162 engageable with breaker arms 163. Each of spark plugs 160 is connected to the high voltage terminal of a conventional induction coil 164, the low voltage circuit of which includes a battery 165 and a make-and-break switch 166 controlled by breaker arm 163. Thus, at the end 30 of each stroke of the free-piston structure, cam rod 161 operates a breaker arm 163 to open the switch at 166 and break the low voltage circuit, thus causing a spark to occur at plug 160 in the 35 conventional manner.

Upon the occurrence of an explosion, say in cylinder 133, the free-piston is driven downwardly, and the acoustic piston head 153 creates a positive pressure pulse which is introduced into horn 131 and traverses the latter to its open end. The explosion frequency of the engine is easily 45 adjusted to the fundamental resonant frequency of the horns 130 and 131, which behave substantially as quarter-wave cavities, with high impedance pressure anti-node regions P at their 50 ends coupled to the free-piston, and with low impedance velocity anti-node regions V at their open ends. Accordingly, the positive pressure pulse launched, for example, down the horn 131 is reflected from the open end thereof as a negative 55 pressure pulse, which arrives with peak negative pressure at the beginning or smaller end of the horn and at the space in cylinder 132 between the horn and piston portion 153 as the latter is mid-way on its upward return stroke. A 60 reflection of this negative pulse occurs, and a negative pulse travels down the horn, to be reflected from the open end as a positive pulse which will pass through the small end of the 65 horn and arrive at piston portion 153 with peak pressure at the mid-point of the down stroke. Both sides of the acoustic piston are thus used for wave generation, the lower cooperating with 70 lower horn 131, and the upper with upper horn 130. A polyphase effect is thereby achieved at the discharge ends of the two horns, with resulting reduction of objectionable noise.

Reference is here made to my continuation-in-part application entitled Acoustic Jet Engine with Centrifugal Fluid Pumping Characteristics, filed

April 24, 1950, Serial No. 157,740, in which the subject matter of Figure 2 of the present application is disclosed and claimed.

The broad invention has now been disclosed by way of a specific description of several illustrative embodiments thereof. It is to be understood of course that these are for illustrative purposes only, and that various changes in design, structure and arrangement may be made without departing from the spirit and scope of the invention as claimed.

I claim:

1. A multiple-circuit quarter-wave pulse jet engine comprising a plurality of substantially quarter-wave fluid filled sonic pipes each substantially closed at a forward end thereof to form a sonic wave reflector, and open at its rearward end for wave expansion and fluid jet discharge, said pipes being grouped and disposed for jet discharge in the same general direction, a pressure pulse means for each of the pipes for producing intermittent positive pressure pulses within the fluid in the closed end portion of the pipe at a frequency to resonate the pipe and establish in the fluid column therein a standing wave having a pressure anti-node at the closed end of the pipe and a velocity anti-node at the open end thereof, all in such manner as to produce fluid velocity oscillations at the open end of each pipe in combination with intermittent jetting of fluid therefrom under control of the corresponding standing wave, and a coupling between said pressure pulse means for the pipes adapted to produce a phase difference between the standing waves in the pipes whereby the velocity oscillations at the open ends of the pipes are out of phase with one another and the jet discharges from the plurality of pipes will occur in succession.

2. An engine as defined in claim 1, wherein the rearward ends of the pipes are disposed in close proximity to one another, so as to provide acoustic intercoupling of the standing waves in the pipes as a result of interaction of fluid velocity oscillations in the region surrounding said velocity anti-nodes.

3. An engine as defined in claim 1, including also means for synchronizing the pressure pulse means to produce standing waves in the sonic pipes having uniform phase difference.

4. An engine as defined in claim 1, in which the sonic pipes are positioned substantially parallel to one another and side by side.

5. An engine as defined in claim 1, in which the sonic pipes are positioned in a longitudinal row, and including means for synchronizing the standing waves in the sonic pipes to operate with uniform phase difference.

6. A multiple circuit quarter wave pulse jet engine comprising a plurality of substantially quarter-wave fluid filled sonic pipes each substantially closed at a forward end thereof to form a sonic wave reflector and open at the rearward end thereof for wave expansion and fluid jet discharge, said pipes being grouped and disposed in the same general direction, means for introducing fuel and air to the closed end portion of each of said sonic pipes and for exploding same at a frequency to resonate said pipes and establish in the fluid column therein standing waves having pressure anti-nodes at the closed ends of the pipes and velocity anti-nodes at the open ends thereof, all in such manner as to produce fluid velocity oscillations at the open end of each pipe in combination with intermittent jetting of fluid

therefrom under control of the corresponding standing wave, and a coupling acting to maintain the standing waves in the pipes with a phase difference between them.

5. 7. An engine as defined in claim 6, wherein the coupling comprehends an interaction of oscillating fluids surrounding the velocity anti-node regions of the pipes.

8. An engine as defined in claim 6, including 10 also fuel feeding means for the pipes operable and synchronized to feed fuel charges to the sonic pipes at equal time intervals in predetermined succession.

9. An engine as defined in claim 6, including 15 also a fuel distributor pump adapted to feed fuel charges to the sonic pipes at equal time intervals in predetermined succession.

10. An engine as defined in claim 6, including 20 fuel feeding means for the pipes, and air feeding means operable and synchronized to feed air charges to the sonic pipes at equal time intervals in predetermined succession.

11. A multiple-circuit quarter-wave pulse jet engine comprising a plurality of substantially 25 quarter-wave fluid filled sonic pipes each substantially closed at a forward end thereof to form a sonic wave reflector, and open at its rearward end for wave expansion and fluid jet discharge, said pipes being grouped and disposed for

30 jet discharge in the same general direction, a pressure pulse means for each of the pipes for producing intermittent positive pressure pulses within the fluid in the closed end portion of the pipe at a frequency to resonate the pipe and establish in the fluid column therein a standing wave having a pressure anti-node at the closed end of the pipe and a velocity anti-node at the open end thereof, all in such manner as to produce fluid velocity oscillations at the open end of

35 each pipe in combination with intermittent jetting of fluid therefrom under control of the corresponding standing wave, the rearward ends of the pipes being disposed in close proximity to one another, so as to provide acoustic inter-

40 coupling of the standing waves in the pipes as a result of interaction of fluid velocity oscillations in the region surrounding said velocity anti-nodes.

12. A multiple circuit quarter wave pulse jet engine comprising a plurality of substantially 50 quarter-wave fluid filled sonic pipes each substantially closed at a forward end thereof to form a sonic wave reflector and open at the rearward end thereof for wave expansion and fluid

55 jet discharge, said pipes being grouped and disposed in the same general direction, a common pipe surrounding and extending rearwardly from said plurality of pipes, forming a common conduit for receiving the jet discharge from all of

60 said pipes and having a common discharge opening to atmosphere at its rearward end, and means for introducing fuel and air to the closed end portion of each of said sonic pipes and for exploding same at a frequency to resonate said

65 pipes and establish in the fluid column therein standing waves having pressure anti-nodes at the closed ends of the pipes and velocity anti-nodes at the open ends thereof, all in such manner as to produce fluid velocity oscillations at the open end of each pipe in combination with intermittent jetting of fluid therefrom into said common

70 surrounding pipe under control of the corresponding standing wave.

13. An engine as defined in claim 12, including

75

means causing the standing waves in the sonic pipes to operate with a phase difference.

14. An engine as defined in claim 12, including fuel feeding means for the sonic pipes timed to establish the standing waves in the pipes with substantially equal phase differences between them.

15. An engine as defined in claim 12, wherein the discharge ends of the sonic pipes are grouped in close proximity to one another to cause an interaction of oscillating fluids surrounding the velocity anti-node regions of the sonic pipes and thereby establish a tendency for acoustic self-coupling with uniform phase relations between the standing waves in the several pipes.
